UNITED STATES PATENT OFFICE.

OSCEOLA C. THOMPSON, OF WHITE PLAINS, NEW YORK, ASSIGNOR TO WIREBOUNDS
PATENTS COMPANY, A CORPORATION OF MAINE.

MACHINE FOR USE IN MAKING BOXES.

1,406,105.

Specification of Letters Patent. Patented Feb. 7, 1922.

Application filed June 2, 1920. Serial No. 386,034.

To all whom it may concern:

Be it known that I, OSCEOLA C. THOMPSON, a citizen of the United States, residing at White Plains, in the county of Westchester, in the State of New York, have invented new and useful Improvements in Machines for Use in Making Boxes, of which the following is a specification.

This invention relates to machines for use in making wirebound boxes, box blanks or parts and particularly to means for severing the binding wire between box blanks or work assemblies.

The nature of the invention will be best understood by reference to one form of machine containing an embodiment thereof, which is shown for illustration in the accompanying drawings.

The machine selected for illustration is a wirebound box blank machine adapted for uninterrupted operation in making a plurality of wirebound box blanks in succession, continuous lengths of binding wire being applied to successive assemblies of box materials; and the purpose of the invention in such illustrative embodiment is to sever the binding wire between successive blanks.

Obviously, the invention is not limited in its application to machines of this particular type.

In the drawings:

Fig. 1 is a side elevation of the illustrative box blank machine, omitting the receiving end portion of the work conveyer.

Fig. 2 is an end elevation of the illustrative box blank machine viewed from the left in Fig. 1.

Fig. 3 is an enlarged end elevation of an individual cutter and the controller therefor.

Fig. 4 is a sectional view taken on the line B—B of Fig. 3.

Fig. 5 is a section taken on the line C—C of Fig. 3.

Fig. 6 is a plan view of the conveyer chain and cutter controlling means seen from the line A—A in Fig. 4.

Figs. 7 to 11 inclusive are diagrammatic sectional views of a cutter showing the positions of the parts during different phases of a cutting operation.

The illustrative machine comprises between supporting side frames 1 a gang of

staplers 2 and a relatively movable work-holder 3 for assembled cleats and side material for a blank or a succession of foldably related box sections.

The work-holder 3 is in the form of a circulating conveyer having work-positioning means for a succession of box blanks; said conveyer comprising a pair of endless link chains appropriately channel-shaped to receive the box cleats and having spacer blocks 4 affixed thereon at intervals for determining proper relationship of adjacent box sections or of the cleats and side material for a blank and for spacing successive blanks apart.

Box sections are successively assembled on the conveyer chains by placing cleats thereon in pairs and laying sheets of side material thereacross; or, if desired, an integral sheet for a blank may be placed upon a succession of cleats.

The conveyer chains run on horizontal guide rails 5 and at the delivery end of the machine are trained around the driven sprocket wheels 6 which may be rotated from the main shaft 7 by any suitable means; for instance, by the ratchet feed mechanism shown in Fig. 1, comprising a ratchet wheel 8 and a coacting feed pawl 9 carried by a lever 10 which is operated through a rod 11 from an eccentric 12.

With the type of feed mechanism described, the conveyer and work thereon will be advanced to the staplers step by step in alternation with the stapling operations; and associated with said mechanism there may be provided any suitable devices, not necessary to be illustrated, for varying, adjusting, or controlling the feed for skipping the stapling operation at the box joints, for manually independently rotating the conveyer sprockets, for initial work adjustment or otherwise, and for braking the conveyer sprockets at the completion of each feed step.

Suitable means for this purpose are shown, for example, in the patent to Thompson, No. 1,258,625, dated March 5, 1918, and in the application of S. F. Bauwens, filed March 22, 1919, Serial No. 284,332.

As the work progresses beneath the staplers, a plurality of continuous lengths of binding wire drawn from suitable supply

reels, not shown, are introduced in proper relation to the box sections to be stapled thereto, the wires being led between the rollers 18 and thence under the rollers 14 5 carried by the stapler bodies, and are pulled along with the work by virtue of their attachment thereto at preceding points. Certain of the wires aligned with the box cleats are stapled through the sheets thereto so 10 as to connect such wires to both the cleats and the sheets and secure the latter together; and intermediate wires are or may be stapled to the sheets alone and clinched on their under sides by coaction of the staple drivers 15 with anvils 15 supported on the cross-frame member 16.

The staplers 2 may be of the type disclosed, for example, in the aforesaid patent to Thompson, No. 1,258,625, comprising combined staple formers and drivers adapted at 20 every operation to cut and form staples from staple-stock wire fed thereto by rollers 17, and to drive the same over the binding wires into the work. Said staplers are mounted 25 on the stationary cross-head 18 and are actuated by the vertically reciprocating cross-bar 19 working in guides of the side frame 1 and operated by a pitman 20 from eccentric 21 on the main shaft, there being similar 30 operating connections at either side of the machine. The feed rollers 17 for the staple-stock wires are also operated from the main shaft by eccentric 22 and connecting rod 23 working a pawl and ratchet device 24 for 35 rotating the rollers intermittently.

With the intermittent feed type of machine described, a staple is formed and driven at every reciprocation of the cross-head 19 or so-called "upper stitcher bar," the 40 staple being driven on the downward stroke thereof, while the material is momentarily at rest, the extent of movement of the material between successive operation of the staplers determining the spacing between 45 successive staples.

It will be understood that this specific machine is but one illustrative example of a machine to which my invention is applicable, in which box parts are successively 50 wired together by effecting relative progression between the work and the fastener-setting mechanism and in which desired relative positions of adjacent box parts are properly maintained during the wiring of 55 such parts together, various constructions and arrangements for these functions being already known to the art.

Referring again to the illustrative machine, as the work leaves the stapling mechanism, the finished blanks may be stripped from the conveyer chains on to table bars 25 suitably supported at the delivery end of the machine.

Before the work is delivered to the table 60 bars 25 and while it is still on the work con-

veyer, the wires connecting one blank and another may be severed by the automatic cutting mechanism presently to be described.

The binding wires are intended to be severed between one blank and the next in 70 such manner as to leave free wire ends projecting beyond the ends of the blank so that when the blank is folded into box form these projecting wire ends may be twisted or otherwise secured together for closing the 75 box. To suit this purpose the materials for succeeding blanks are suitably spaced to leave between them a sufficient length of wire to provide, when severed, the desired 80 free ends. Such spaces may be effected, for example, by placing the group of work-positioning devices or spacer blocks for one blank somewhat ahead of the group for the next blank.

Mechanism for severing the binding wires 85 is located at the delivery end of the machine directly behind the staplers and consists of a plurality of individual cutters corresponding in number to the staplers and adapted to be controllably operated at selected times to 90 sever the wire between box blanks or work assemblies.

The individual cutters are secured to the back plates of the lower stapler bodies carried by cross-bar 18 and are actuated by 95 the vertically reciprocating cross-bar 19 through the medium of plunger arms 30 pivotally hung from studs 37 attached to the back plates of the upper stapler bodies. Said plunger arms 30 are constructed and 100 arranged to reciprocate normally with the upper cross-bar 19 without operating the cutters and at selected times are thrown into operating connection with the cutters to cause a wire-severing operation.

An individual cutter consists of the stationary knife 31 carried by the back plate of the cutter and the swinging knife 32 pivotally suspended from a plate 33 reciprocable vertically in guides 34 of the cutter casings 110 and maintained in normal non-cutting position by a spring 51. Plate 33 carrying knife 32 is adapted to be lowered and raised at selected times by the plunger 30 to effect a 115 wire-severing operation.

As best shown in Figs. 7 to 11 inclusive, knife 32 is beveled at its lower extremity and its cutting edge 35 is formed in an opening or notch in the knife so that when the knife is lowered against a wire to be severed, the 120 wire will contact with the beveled extremity of the knife and force it to one side against the action of a spring 36, as shown in Fig. 9. Continued lowering of knife 32 will cause the cutting edge 35 to pass below the 125 wire, whereupon spring 36 will swing cutting edge 35 under the wire, which will then lie above cutting edge 35 of knife 32 and below the cutting edge of knife 31 (see Fig. 10) in position to be severed between knives 130

31 and 32, when knife 32 is raised, as shown in Fig. 11.

Plunger arm 30 for causing the lowering and raising of knife 32, which is pivotally suspended from stud 37 and reciprocates constantly in guides 38 of the cutter, is normally maintained by a spring 39 in inoperative position against the left-hand side of guides 38 in Fig. 3 so that reciprocation thereof will not effect a cutting operation. Plunger arm 30 and plate 33 carrying knife 32, are provided with controllable interlocking means to effect a connection between the two for a severing operation. Such means may comprise the opening or notch 40 formed in plunger arm 30 which is adapted to engage a projection 41 on the plate 33 and carry the plate 33 and knife 32 down and up with arm 30.

For causing the plunger arm 30 and the plate 33 to engage, means are provided to swing arm 30 as it descends, toward the projection 41 so that projection 41 will snap into notch 40 when they meet. Such means may consist of the spring-pressed trigger 42 carried by a block 43 adjustably secured to a bar 44 slidably mounted in the cutter casings; said trigger 42 being adapted to enter opening 45 in the cutter casing and engage plunger arm 30 to swing it toward projection 41 and maintain it in such position during a wire-severing operation. It will be noted that the lower extremity of plunger arm 30 is beveled at one side to engage trigger 42 and at the other side to engage projection 41.

Trigger 42 is caused to enter opening 45 at proper times for a wire-severing operation by movement of bar 44 against the action of spring 46. Mechanism is provided for moving bar 44 at proper times to effect a wire-severing operation. Such mechanism may consist of the cams 47 adjustably secured at selected points to the conveyer chains 2 by set screws 48 or in any other suitable manner and the lever 49 pivoted at 50 to the cutter casing of one of the outside cutters and preferably pivotally connected at its upper end to the compression spring 54 carried by bar 44. The lower end of lever 49 normally hangs in the path of travel of the cams 47 so that movement of a cam 47 against the lower end of lever 49 will cause lever 49 to pivot about point 50 and, by compressing spring 54, move bar 44 against the action of spring 46. Movement of bar 44 to the right in Fig. 7 causes trigger 42 to enter opening 45 and, by contacting with plunger arm 30, to force it into operating connection with the plate 33 to operate the cutter. The cams 47, as shown in Fig. 6, are constructed and arranged to move trigger 42 into operating position in the path of plunger 30 and hold it there until the plunger arm has been lowered and

raised by the action of the cross-bar 19. When a cam 47 has passed lever 49, bar 44 and lever 49 are returned to initial position through the action of springs 46 and 54. In the illustrative machine the cams 47 for controlling the operation of the cutters are attached, for convenience, to one of the spacer blocks 4; preferably the last block for each blank, and are so constructed and arranged that the cutters will be thrown into operation at proper times to sever the wire at the desired distance from edges of the work and after staples have been driven into the oncoming box materials.

For disengaging plunger arm 30 from projection 41 when trigger 42 is released, plunger arm 30 is provided with a cam surface 52 adapted to engage a cam surface 53 in the guide 38 after the completion of a wire-severing operation.

It will be noted that the bar 44, which is controlled and actuated by the work-forwarding means through the cams 47, passes through all the individual cutters and is provided with a block 43 and trigger 42 for each cutter so that the shifting of bar 44 through the action of cams 47 on lever 49 causes a trigger 42 to enter each cutter and effect an operating connection between plunger arm 30 and the knife 32; thus, all the cutters are operated together and the wires will be uniformly severed.

It will also be noted that the cutters are actuated by the so-called "upper stitcher bar" 19 which also actuates the staplers, and that the wires are severed upon the up stroke of said stitcher bar. One advantage, among others, in severing the wire upon the up stroke of the "upper stitcher bar" is that it insures the driving of at least one staple 105 into the oncoming box materials to hold the wire in position before it is severed; a staple being driven upon each down stroke of said bar.

The operation of an individual cutter is clearly illustrated in Figs. 7 to 11 inclusive. In Fig. 7 the plunger arm 30 is descending and the controlling cam 47 is about to engage the lever 49. In Fig. 8 the cam 47 has engaged lever 49 and pivoted it about its pivot point 50, thereby causing trigger 42 to enter the cutter and throw plunger arm 30 into engagement with plate 33. In Fig. 9, plunger arm 30 is forcing knife 32 downward against the wire to be severed and the wire is swinging knife 32 to one side. In Fig. 10, knife 32 has snapped in under the wire and plunger arm 30 is about to start upward to effect a severing operation. In Fig. 11, knife 32 has risen and the wire has been severed between the cutting edges of knives 31 and 32; and plunger arm 30 is about to be disengaged from the plate 33 by the coaction of cam surfaces 52 and 53. Cam 47 will then have released lever 130

49 and plunger arm 30 will reciprocate idly in guides 38 until the next cam 47 engages lever 48.

It will be noted that knives 31 and 32 are both maintained normally in inoperative position above the plane of the work and that by lowering swinging knife 32 against the wire to be severed, it will be swung to one side by the wire and its cutting edge will snap in under the wire in position to carry the wire up with it when raised and cause the wire to be severed between the cutting edges of the knives 31 and 32. Thus, it will be seen that while both cutting members are normally maintained above the plane of the work during the intervals between cutting operations the swinging cutting member automatically assumes an operative position below the wire when lowered against it and performs a severing operation when raised.

It will also be noted that the movable knife 32 is located behind the stationary knife 31 in the line of travel of the work. Thus the severed end of the wire attached to the completed blank will be raised with the movable knife and the severed end of the wire attached to the oncoming blank will be held below the operating plane of the cutting members and will be free to advance without buckling when the oncoming blank is again moved forward.

Power for operating the machine may be applied in any suitable manner as, for instance, by power pulley 55, shown in Fig. 2, which may be controllably clutched to the shaft 7 by any suitable clutch mechanism.

Obviously, the present invention is not limited to the particular embodiment shown and described but may be variously embodied and the particular construction shown may be variously modified, as will appear to those skilled in the art. Furthermore, it is not indispensable that all the features of the invention be used conjointly since they may be used to advantage in various different combinations and sub-combinations.

Having described the invention, what is claimed is:

1. A machine for use in making wirebound boxes comprising, in combination, a work support; fastener-setting mechanism for applying binding wire to a succession of box assemblies; means for spacing said assemblies; means to cause relative progression between said mechanism and the box assemblies; and means to sever the binding wire between box assemblies, including a vertically reciprocable cutting member operable upon its up stroke: said machine being organized for uninterrupted operation upon a succession of box assemblies.

65 2. A machine for use in making wire-

bound boxes comprising, in combination, a work support; fastener-setting mechanism for applying binding wire to box parts; means to cause relative progression between said mechanism and the box parts; and means controlled by said relative progression for severing the binding wire between box parts, including a vertically reciprocating cutting member operable upon its up stroke; said machine being organized for uninterrupted operation upon a succession of box assemblies.

3. A machine for use in making wirebound boxes comprising, in combination, a work support; fastener-setting mechanism for applying binding wire to box parts; means to cause relative progression between said mechanism and the box parts; means to sever the binding wire between box parts; and a vertically reciprocating actuator therefor operable upon its up stroke: said elements constituting an organization adapted to operate without interruption upon a succession of box assemblies.

4. A machine for use in making wirebound boxes comprising, in combination, a work support; fastener-setting mechanism for applying binding wire to box parts; means to cause relative progression between said mechanism and the box parts; means to sever the binding wire between box parts; and a vertically reciprocating actuator therefor controlled by said relative progression and operable at selected times upon its up stroke; said machine being organized for uninterrupted operation upon a succession of box assemblies.

5. A machine for use in making wirebound boxes, comprising, in combination, a work support; fastener-setting mechanism for applying binding wires to box parts; means to cause relative progression between said mechanism and the box parts; and means to sever the binding wires between box parts comprising a plurality of individual cutters, each having a vertically reciprocating cutting member operable upon its up stroke.

6. A machine for use in making wirebound boxes comprising, in combination, a work support; fastener-setting mechanism for applying binding wires to box parts; means to cause relative progression between said mechanism and the box parts; means to sever the binding wires between box parts after said wires have been applied to said box parts comprising a plurality of individual cutters; and a vertically reciprocating actuator therefor operable upon its up stroke.

7. A machine for use in making wirebound boxes comprising, in combination, a work support; fastener-setting mechanism for applying binding wire to box parts; means to cause relative progression between said mechanism and the box parts; and means to sever the binding wire between box parts,

- including a vertically reciprocating cutting member normally maintained above the wire to be severed and adapted at selected times to be lowered beneath the wire and sever it upon the up stroke of the cutting member. 8
8. A machine for use in making wirebound boxes comprising, in combination, a work support; fastener-setting mechanism for applying binding wire to box parts; means to cause relative progression between said mechanism and the box parts; means to sever the binding wire between box parts, including a vertically reciprocating cutting member normally maintained above the wire to be lowered beneath the wire and sever it upon the up stroke of the cutting member; and means for controlling the operation of said severing means. 15
- 20 9. A machine for use in making wirebound boxes comprising, in combination, a work support; fastener-setting mechanism for applying binding wire to box parts; means to cause relative progression between said mechanism and the box parts; means to sever the binding wire between box parts, including a vertically reciprocating cutting member normally maintained above the wire to be lowered beneath the wire and sever it upon the up stroke of the cutting member; and means moving with the work for controlling the operation of said severing means. 25
- 30 10. A machine for use in making wirebound boxes comprising, in combination, a work support; fastener-setting mechanism for applying binding wire to box parts; means to cause relative progression between said mechanism and the box parts; and means controlled by said relative progression for severing the binding wire between box parts, including a vertically reciprocating cutting member normally maintained above the wire to be lowered beneath the wire and sever it upon the up stroke of the cutting member. 35
- 40 11. A machine for use in making wirebound boxes comprising, in combination, a work support; fastener-setting mechanism for applying binding wire to box parts; means to cause relative progression between said mechanism and the box parts; and means to sever the binding wire between box parts comprising a stationary cutting member and a vertically reciprocating cutting member adapted, upon reciprocation downward, to pass beneath the wire to be severed and, upon reciprocation upward, to sever the wire by co-action with the stationary cutting member. 45
- 50 12. A machine for use in making wirebound boxes comprising, in combination, a work support; fastener-setting mechanism for applying binding wire to box parts; means to cause relative progression between said mechanism and the box parts; and means controlled by said relative progression for severing the binding wire between box parts comprising a stationary cutting member and a vertically reciprocating cutting member adapted upon reciprocation downward to pass beneath the wire to be severed and upon reciprocation upward to sever the wire by co-action with the stationary cutting member. 55
- 60 13. A machine for use in making wirebound boxes comprising, in combination, a work support; fastener-setting mechanism for applying binding wire to box parts; means to cause relative progression between said mechanism and the box parts; and means to sever the binding wire between box parts comprising a stationary cutter and a swing cutter, said swing cutter being reciprocable vertically and adapted when lowered against a wire to swing out and under said wire and when raised to sever said wire by co-action with the stationary cutter. 65
- 70 14. A machine for use in making wirebound boxes comprising, in combination, a work support; fastener-setting mechanism for applying binding wire to box parts; means to cause relative progression between said mechanism and the box parts; means to sever the binding wire between box parts comprising a stationary cutter and a swing cutter, said swing cutter being reciprocable vertically and adapted when lowered against a wire to swing out and under said wire and when raised to sever said wire by co-action with the stationary cutter; and means for controlling the reciprocation of said swing cutter. 75
- 80 15. A machine for use in making wirebound boxes comprising, in combination, work-forwarding means; means for applying binding wire to box parts; means to sever the binding wire between box parts; and a vertically reciprocating actuator therefor operable upon its up stroke and controlled by the work-forwarding means. 85
- 90 16. A machine for use in making wirebound boxes comprising, in combination, work-forwarding means; means for applying binding wire to box parts including a vertically reciprocating actuator therefor; and means for severing the binding wire between box parts after it has been applied to said box parts operable upon the up stroke of said reciprocating actuator. 95
- 100 17. A machine for use in making wirebound boxes comprising, in combination, work-forwarding means; means for applying binding wire to box parts, including a vertically reciprocating actuator therefor; and means for severing the binding wire between box parts actuated by the up stroke of said reciprocating actuator; said machine being adapted to operate without interruption upon materials for a plurality of boxes. 105
- 110 120
- 125 130

18. A machine for use in making wire-bound boxes comprising, in combination, work-forwarding means; means for applying binding wire to box parts, including a vertically reciprocating actuator therefor; and means for severing the binding wire between box parts controlled by the work-forwarding means and operable upon the up stroke of said reciprocating actuator.
19. A machine for use in making wire-bound boxes comprising, in combination, work-forwarding means; means for applying binding wire to box parts, including a vertically reciprocating actuator therefor; and means for severing the binding wire between box parts after it has been applied thereto, said means being actuated at selected times by the up stroke of said reciprocating actuator.
20. A machine for use in making wire-bound boxes comprising, in combination, work-forwarding means; means for applying binding wire to box parts, including a vertically reciprocating actuator therefor; and wire-severing means controlled by the work-forwarding means and actuated by the up stroke of said reciprocating actuator.
21. A machine for use in making wire-bound boxes comprising, in combination, work-forwarding means; means for applying a plurality of binding wires to box parts, including a vertically reciprocating actuator therefor; and a plurality of individual wire cutters, one for each of said plurality of wires, operable simultaneously upon the up stroke of said reciprocating actuator; said machine being adapted to operate without interruption upon materials for a plurality of boxes.
22. A machine for use in making wire-bound boxes comprising, in combination, work-forwarding means; means for applying a plurality of wires to box parts, including a vertically reciprocating actuator therefor; and a plurality of wire cutters adapted to sever said wires between box parts after they have been applied to said box parts, said cutters being actuated simultaneously at selected times by the up stroke of said reciprocating actuator.
23. In a machine of the class described adapted for uninterrupted operation upon a plurality of box assemblies, mechanism automatically to sever binding wires between box assemblies, comprising a pair of relatively movable cutting members and a vertically reciprocating actuator therefor operable upon its up stroke.
24. In a machine of the class described, mechanism automatically to sever the binding wires between box assemblies after it has been secured thereto, comprising a plurality of pairs of relatively movable cutting members and a common vertically reciprocating actuator therefor operable upon its up stroke.
25. In a machine of the class described, mechanism automatically to sever the binding wire between box assemblies after it has been secured thereto comprising a stationary cutting member, a swinging cutting member, and a vertically reciprocating actuator operable upon its up stroke to cause relative movement between said cutting members.
26. In a machine of the class described, mechanism automatically to sever the binding wire between box assemblies comprising a stationary cutter and a swing cutter normally held above the plane of the work; means for moving the swing cutter below a wire and for raising it again to sever the wire between said cutters.
27. In a machine of the class described, mechanism automatically to sever the binding wire between box assemblies comprising a stationary cutter above the plane of the work; a swing cutter normally held above the plane of the work but adapted to be lowered and swung under a wire and to be raised and cooperate with said stationary cutter; and means for lowering and raising said swing cutter.
28. In a machine of the class described, mechanism automatically to sever binding wire between box assemblies, comprising a stationary cutting member and a movable cutting member, both normally maintained above the plane of the work; the movable cutting member being constructed and arranged to assume automatically a cutting position below the wire to be severed when lowered against it.
29. A machine for use in making wire-bound boxes comprising, in combination, work-forwarding means; mechanism for applying binding wire to a succession of box blanks progressively subjected to the action thereof; and wire-severing mechanism adapted automatically to sever the wire between each wired blank and the blank being wired, comprising a stationary cutting member and a movable cutting member normally maintained above the plane of the work; said movable cutting member being constructed and arranged to assume, when lowered, an operative position below the wire to be severed and, when raised, to cooperate with said stationary cutting member to sever the wire in such a manner that the severed end of the wire attached to the blank being wired will lie below said cutting members when the severing operation is completed.
30. A machine for use in making wire-bound boxes comprising, in combination, means to apply binding wire to box parts; and means to sever the binding wire between box parts, including a cutting member normally maintained above the plane of the

work but adapted to assume a position below a wire and sever the wire upon the up stroke of said cutting member.

31. A machine for use in making wire bound boxes comprising, in combination, means to apply binding wire to box parts; and means to sever the binding wire between box parts, comprising relatively movable cutting members normally maintained above the plane of the work and means to lower one of said members below the wire to be severed and to raise it again, whereby the wire is severed upon the up stroke of said member.

32. A machine for use in making wire bound boxes comprising, in combination, means to apply binding wire to box parts; and means to sever the binding wire between box parts, comprising relatively movable cutting members normally maintained above the plane of the work, one of said members being adapted to move below the wire to be severed and then move upward, severing the wire on the up stroke.

33. In a machine for use in making wire bound boxes, in combination, mechanism for applying binding wire to box parts; and cutting mechanism for severing the binding wire between box parts, comprising relatively movable cutting members normally maintained above the plane of said wire, one of said members being constructed and arranged to move below the wire to be severed and then move upward, severing the wire on the upstroke, and controlling and actuating means therefor.

34. A machine for use in making wire bound boxes comprising, in combination, means to apply binding wire to box parts; and means to sever the binding wire between box parts including a cutting member normally maintained above the plane of the work and adapted at intervals to assume a cutting position below the work.

35. A machine for use in making wire bound boxes comprising, in combination, means to apply binding wire to box parts; means to sever the binding wire between box parts including a cutting member normally maintained above the plane of the work and adapted at intervals to assume a cutting position below the work; and means to control the operation of said severing means.

36. A machine for use in making wire bound boxes comprising, in combination, means to apply binding wire to box parts; and means to sever the binding wire between box parts including a cutting member normally maintained above the plane of the work and adapted when lowered against a wire to assume a cutting position below the wire.

37. A machine for use in making wire bound boxes comprising, in combination, means to apply binding wire to box parts;

means to sever the binding wire between box parts including a cutting member normally maintained above the plane of the work and adapted when lowered against a wire to assume a cutting position below the wire; and means to lower said cutting member at selected times.

38. A machine for use in making wire bound boxes comprising, in combination, means to apply binding wire to box parts; means to feed the box parts to the binding-wire-applying means; means to sever the binding wire between box parts including a cutting member normally maintained above the plane of the work and adapted when lowered against a wire to assume a cutting position below the wire; and means controlled in accordance with the passage of the work through the machine to lower said cutting member at selected times.

39. A machine for use in making wire bound boxes comprising, in combination, means to apply binding wire to box parts; and means to sever the binding wire between box parts including a cutting member normally maintained above the plane of the work and adapted when lowered against a wire to swing to one side thereof and snap in beneath the same.

40. A machine for use in making wire bound boxes comprising, in combination, means to apply binding wire to box parts; and means to sever the binding wire between box parts including a plurality of cooperating cutting members normally maintained above the plane of the work one such member being adapted to assume a position below the wire prior to the cutting operation.

41. A machine for use in making wire bound boxes comprising, in combination, means to apply binding wire to box parts; and means to sever the binding wire between box parts including a pair of relatively movable cutting members normally maintained above the plane of the work one such member being adapted to assume a position below a wire and sever it by cooperation with said other member.

42. A machine for use in making wire bound boxes comprising, in combination, means to apply binding wire to box parts; means to sever the binding wire between box parts including a pair of relatively movable cutting members normally maintained above the plane of the work one such member being adapted to assume a position below a wire and sever it by cooperation with said other member; and means to cause such cooperation.

43. A machine for use in making wire bound boxes comprising, in combination, means to apply binding wire to box parts; means to sever the binding wire between box parts including a pair of relatively movable cutting members normally maintained above

the plane of the work one such member being adapted to assume a position below a wire and sever it by cooperation with said other member; and controllable means to cause such cooperation at selected times.

44. A machine of the class described comprising, in combination, means to secure binding wire to box parts; work-presenting means; and wire-severing means comprising individual binding wire cutters having co-operating shear devices one adapted to snap under a wire and the other to coact therewith to sever the wire.

45. A machine of the class described comprising, in combination, means to secure binding wire to box parts; means to cause relative progression between the work and wire-securing means; a wire-cutting device pivoted to swing above the work; and means

whereby said device is supported normally 20 in inoperative position and permitted to assume operative position below the work at desired intervals in the work.

46. A machine for use in making wire-bound boxes comprising, in combination, 25 wire-securing mechanism; a work-holder for presenting assembled cleats and side material to said wire-securing mechanism including channel shaped conveyers; and means for severing binding wire between 30 cleats operating in the vertical plane of the cleats entirely within the confines of the supporting and guiding surfaces of a conveyer.

In testimony whereof, I have signed my 35 name to this specification.

OSCEOLA C. THOMPSON.
